CONDENSER

John Ralph Holmes and Adolf Schwarz, Lockport,
N. Y., assignors to General Motors Corporation,
Detroit, Mich., a corporation of Delaware

Application August 2, 1947, Serial No. 765,730

8 Claims. (Cl. 257—28)

1

This invention relates to heat exchangers of the type employing a bundle of finned tubes supported at opposite ends by header plates and an object of the invention is to make feasible the use of relatively long tubes by additionally supporting and binding together the several tubes at one or more places intermediate their length for increased rigidity and a lessening of individual tube vibration and fatigue thereby enabling thinner wall tubing to be used.

In the particular embodiment to be referred to the relatively long tubes carry exterior fins, which consist of helical windings of wire coils extending in one piece from end to end of each tube and the mutual intersupport of the several tubes from one another and from their enclosing housing is easily and cheaply effected by fitting spacer sleeves to intermediate portions of the finned tubes, with each sleeve locked against axial displacement by a simple deformation in the fin portions near opposite ends of the spacers and with the neighboring spacer sleeves engaging one another and being crowded together within an encircling tensionable band firmly located by clamping abutments adjustably carried by the enclosing housing.

A better understanding of the structure will be had from the accompanying drawing wherein Figure 1 is an elevation of a long cylindrical condenser structure having a portion of the housing wall broken away and shown in section; Figure 2 is a transverse section on a larger scale, as on line 2—2 of Figure 1; Figure 3 is a longitudinal section, as on line 3—3 of Figure 2 and on a still larger scale; Figure 4 is an enlarged transverse section of one of the tube subassemblies as viewed on line 4—4 of Figure 3.

In the drawing a bank of spaced tubes 1 is illustrated as being enclosed within a cylindrical shell or housing 2, with each tube supported at opposite ends by the header plates 3 and 4, the attachment of the tubes and header plates being effected by any suitable manner, such as by fitting the end into preformed openings in the header plate and by expanding or flaring the tube end, as best seen in Figure 3. Secured to the header plate 3 is a domed cover 5 containing two chambers with a coupling fitting 6—6 for each, one of the fittings being for the inlet and the other for the outlet of cooling fluid to flow through the tubes. To the opposite end plate 4 there is secured a domed cover 7 having a single chamber communicating with all the tubes so that the cooling fluid flowing from the inlet chamber in the cover 5 and through one set of

2

the tubes 1 will be directed by the chambered cover 7 through the remaining set of tubes to the outlet chamber in the opposite end cover 5. Secured to the wall of the housing shell 2 are one or more inlet fittings 8—8 and one or more outlet fittings 9—9 for the flow through the housing and around the outside of the tubes of the fluid to be cooled, which in the case of a condenser for a refrigerating medium will enter the housing as a gas and upon being condensed will leave the housing as a liquid.

Each tube assembly prior to its mounting in the end plates will have fin formations formed thereon. The finned tube subassembly, as shown 15 in the drawing, includes the tube 1 formed of brass and having fixed thereon closely adjacent each end a steel collar 10 held by extruding the tube against the collar and being covered with copper brazing material and serving to anchor 20 the opposite ends of the coiled fin 11. The fin is preformed by winding steel wire on a suitable mandrel and then copper flashed. One end of the coiled fin is then inserted in an opening through one of the end collars 10 and is peened 25 tightly and then the coil is wound spirally around the tube entirely along the length of the tube to the opposite end collar 10 into an opening of which the other end of the fin wire is inserted and peened tightly. Thereafter the tube assembly is placed in a brazing furnace whereby the 30 parts are firmly joined together. After furnace brazing a spacer sleeve 12, preferably of a split ring type, whose internal diameter approximates or initially is slightly less than the external diameter of the fin 11 is slipped from one end of the tube over the wire fins to a selected intermediate location on the tube assembly. Its split 35 ring construction 12' will enable whatever diametrical expansion and contraction is required to insure a tight fit to the perimeter of the wire fins even though a wide range of manufacturing tolerance is prescribed for the fins. Following proper lengthwise location of the spacer sleeve 12 one or more coils in the fin convolution near 40 each end of the sleeve are pinched or otherwise deformed so as to be projected radially outwardly as at 13 and thereby form stop abutments for cooperation with the sleeve ends to limit axial displacement of the sleeve.

Upon arranging a proper number of the tubes in a group to fit the size of the housing shell 2 and with each spacer sleeve in contact with spacer sleeves of neighboring tubes, the assembly of tubes is wrapped within an encircling band 55 or metal strap 14 which is placed under tension

to crowd the tubes together for their mutual inter-support, by means of a clamping screw bolt 15 joining together the abutting opposite ends of the band 14. The band preferably is a relatively thin flexible sheet strap to bend readily around the corners or otherwise conform to whatever peripheral outline is defined by the tube bundle, whether polygonal sided as shown or otherwise. To afford ample bearing for the clamping screw 15, the ends of the strap are provided with thickened blocks 16-16, one having a tapped hole to receive the screw threads of the clamping bolt and the other having an apertured locating lug for the screw head. At intervals around its circumference the contractible strap may be engaged by or have secured thereto additional thickened block portions or shoes 18 and the several blocks provide for distribution of radially inward pressure on the tube assembly transmitted by adjustable abutment elements carried by the housing. These abutments in the form illustrated consist of a series of set screws 19 threaded through the wall of the housing to engage the pressure distributing plates 18 and thereby firmly locate and support the intermediate portion of the bank of tubes. After initially setting up the series of set screws 19 they may be locked against accidental displacement by peening, soldering or otherwise. The inward contraction of the tube bank encircling structure will insure a snug fit of the spacer sleeves against each other with each split spacer being capable of further contraction under pressure imposed thereon to take out all looseness and insure a firm support for the intermediate portions of the relatively long heat exchanger tubes. A spacer and stiffener bar 20 may, if desired, be positioned diametrically of the encircling band 14 and midway between the group of tubes.

It will be noted from the drawing that the housing 2 is formed in sections, the main section being relatively long and joined for convenience by a torch brazing operation in end to end relation with the two short length end sections. The latter are brazed or otherwise joined to the tube plates 3 and 4 containing the spaced apertures in which the tube ends are fitted. The joint between each tube plate and its adjacent housing end section is indicated in the drawing at 21, while the numeral 22 indicates the line of jointure between the respective housing end sections and the main housing shell. Division of the housing shell into sections eliminates the need for making a torch brazed joint at 21 after the tube plates are fitted to the tubes as would be necessary in the final assembly of the tube plates to a single piece shell and the heat from which would tend to set up oxidation between the tube ends expanded into the tube plates. With the present structure the assembly of the condenser is conveniently effected by first furnace brazing the housing end sections to the plates at 21. Thereafter one of the tube subassemblies has the tube ends of the previously finned and assembled bank of tubes fitted and joined thereto and then the main housing section is slid over the tube bank from the opposite end and the other tube plate subassembly is joined to the opposite tube ends with the abutting portions of the shell sections fitted together through internesting shouldered formations thereon, as seen in Figure 3. Thus the internested housing joints may thereupon be torch brazed at 22 without the likelihood of intense heat flowing to and inducing oxidation at

the expanded and flared tube end joints with the tube plates.

We claim:

1. In a heat exchanger of the character described, a housing having a pair of tube plates, a bundle of finned tubes supported at opposite ends by said tube plates, and flexible means to support the tube bundle intermediate its ends, including spacer sleeves snugly embracing the finned tubes, each sleeve in abutment with adjacent sleeves on neighboring tubes, projecting formations on the tube fins immediately beyond the sleeves for locating the sleeves against axial displacement, a tube bundle encircling strap engaging the spacer sleeves on the outermost tubes, strap tensioning means contracting the strap for crowding the sleeves in clamped together relation and a series of spaced seating abutments adjustably mounted in the wall of the housing and engaged with said strap to support the intermediate portion of the tube bundle.
2. In a heat exchanger wherein a housing encloses a series of long tubes supported in spaced apart tube plates, and each tube has wound thereon a coiled fin, means to support the tubes intermediate said tube plates including a tensionable strap embracing the intermediate portion of the tube assembly and supported by the housing, a series of tube spacers engaging several fin convolutions of each tube and cooperating with said strap in clamping the tube assembly and said spacers being held against axial displacement by end engagement with deformations in the tube fins.
3. In a heat exchanger having a series of finned tubes, flexible means to brace the tubes from one another intermediate their length including a plurality of split spacer sleeves embracing the tube fins, one on each of said tubes, each of said sleeves engaging neighboring sleeves, and a tensionable band encircling the tube assembly and engaging the split sleeves on the outermost tubes to crowd the sleeves together and individually into snug fit with the fins embraced thereby.
4. In combination, a group of spaced tubes, a helical coil of wire helically wrapped on each tube and a spacing collar embracing several wrappings of coiled wire intermediate opposite ends of each tube, said wires adjacent the ends of the several collars having convolutions distorted so as to project radially beyond the collar embraced convolutions and thereby restrain axial collar shift.
5. In combination, an assembly of spaced tubes each having wrapped thereon a coil fin wire and intermediate tube spacer sleeves, each sleeve having an internal diameter such as to fit snugly certain of the coils, said wire immediately next to the sleeve ends being formed so as to project in stop abutment relation with the sleeve ends for sleeve retention against axial shift.
6. In a heat exchanger having a series of finned tubes, flexible means to brace the tubes from one another intermediate their length comprising, a plurality of contractible spacer sleeves embracing the tube fins, one on each of said tubes, each of said sleeves engaging neighboring sleeves, and tensionable supporting means for crowding together and contracting the contractible spacer sleeves.
7. In a heat exchanger having a series of finned tubes, flexible means to brace the tubes from one another intermediate their length comprising, a plurality of contractible spacer sleeves embracing the tube fins, one on each of said tubes, each of said sleeves engaging neighboring sleeves, retainer

formations carried by the tubes for end engagement with the spacer rings to locate the same against axial displacement, and tensionable supporting means for crowding together and contracting the contractible spacer sleeves.

8. In a heat exchanger, a housing, a bundle of finned tubes within the housing, flexible interengaging spacers sleeved on the finned tubes intermediate their length, a tensionable band surrounding the tube assembly in the region of said spacer sleeves, a series of circumferentially spaced supporting and locating devices carried by the housing and engaged with the band, and means for adjusting said devices radially inwardly.
